CLAIM

The ornamental design for a hydroponics system, as shown and described.

DESCRIPTION

FIG. 1 is a front, top, right side perspective view of the hydroponics system showing our new design;
FIG. 2 is a left side elevational view thereof;
FIG. 3 is a rear elevational view thereof; and,
FIG. 4 is a bottom plan view thereof, showing the tray in another position.

The cord-like elements are shown throughout the drawings in varying positions due to their nature.
